US0D1026196S

(12) **United States Design Patent** (10) Patent No.: **US D1,026,196 S**
(45) Date of Patent: ** May 7, 2024

(54) **AIR FRESHENER FOR VEHICLES**

(71) Applicant: **Park & Works**, Busan (KR)

(72) Inventor: **Sang Wook Park**, Busan (KR)

(73) Assignee: **PARK & WORKS**, Busan (KR)

(**) Term: **15 Years**

(21) Appl. No.: **29/843,598**

(22) Filed: **Jun. 22, 2022**

(30) **Foreign Application Priority Data**

Dec. 31, 2021 (KR) 30-2021-0063657
